UNITED STATES PATENT OFFICE.

CECIL T. FARMER, OF FRANKFORT, KENTUCKY.

DESIGN FOR A GARMENT-RACK.

49,664.

Specification for Design.

Patented Sept. 19, 1916.

Application filed July 17, 1916. Serial No. 109,838. Term of patent 14 years.

To all whom it may concern:

Be it known that I, CECIL T. FARMER, a citizen of the United States, residing at Frankfort, in the county of Franklin and State of Kentucky, have invented a new, original, and ornamental Design for a Garment-Rack, of which the following is a specification, reference being had to the accompanying drawing, forming part thereof.

The figure is a perspective view of a garment rack showing my new design.

I claim:—

The ornamental design for a garment rack, as shown.

CECIL T. FARMER.

Witnesses:

A. C. MORRIS,
W. S. FARMER.
